UNITED STATES PATENT OFFICE

WALTER EDWARD KIMBER, OF LONDON, ENGLAND

MEANS FOR DRAWING CURTAINS AND THE LIKE

Application filed August 16, 1928, Serial No. 300,091, and in Great Britain August 16, 1927.

This invention relates to a new or improved method of and means for drawing curtains or the like and has for its object to lessen wear and tear, increase the length of life of the curtain and at the same time to ensure efficient and easy opening and closing thereof.

Curtains are usually drawn by cords or the like attached to the rings or the like, or to the curtains themselves, and the opening as well as the closing is effected by pulling on the first of the hooks supporting the curtain. Thus, in closing or unfolding the curtain, the first hook or adjacent part is subjected to a pull which is continued throughout the operation and the folds being gradually unfolded and drawn, the remaining hooks are also pulled although not to so great an extent as the first hook. Thus the hooks not only support the weight of the curtain but also transmit the pull of the actuating cords to the curtain. Such continual straining, particularly on the first hook, eventually results in the distortion and/or tearing of the curtain. This disadvantage is accentuated with the heavy curtains now in use in kinemas and theatres and the avoidance of damage to such expensive material is highly desirable.

According to this invention the objections noted are removed by arranging that the closing or unfolding of the curtain or the like commences at the following or last folds or pleats and continues progressively along the curtain to the first or leading fold. This operation is suitably effected by providing a slidable device for supporting the curtain rings or the like during their movement along the rod. In this manner the curtain supporting devices merely support the weight of the curtain, the pulling strain of the actuating cords being taken mainly by the movable device. This movable device preferably consists of a slide or carrier mounted on or in the curtain rod and formed with an upper inclined or cam surface so that as the device is traversed the curtain rings or the like are released or collected in an easy manner according to whether the curtain is being closed or opened.

In order to enable the invention to be readily understood, reference is made to the accompanying drawings, illustrating several different constructions and arrangements by way of example, in which drawings:

Figure 1 is a perspective view of means embodying these improvements for the drawing of a double curtain, portions of the construction being broken away to enable certain parts to be more clearly seen, and for the sake of convenience the curtains are shorter and fewer curtain rings are shown than would be the case in actual practice.

Figure 2 is a plan view partly in section of the apparatus shown in Figure 1.

Figure 3 is an end elevation looking in the direction of the arrow, Figure 1.

Figure 4 is a front elevation illustrating the position of the right hand carrier shown in Figure 1 in the folded or opened condition of the curtain.

Figure 5 is an elevation, partly in section and having parts broken away, of a modified construction adapted for the drawing of a single curtain.

Figure 6 is an end view of the right hand end of Figure 5.

Figure 7 is a section on the line VII—VII of Figure 5.

Figure 8 is a plan view partly in section of a modified arrangement for drawing a heavy double curtain.

Figure 9 is a perspective view of a modified form of carrier and curtain rod.

Figure 10 is a perspective view illustrating the application of the invention to a curved curtain rod and

Figure 11 is a perspective view of a modified construction of slidable carrier.

Referring to the construction of apparatus shown in Figures 1 to 4, *a* is a tubular curtain rod supported by brackets *b* from a mounting *c*. The rod *a* is provided with a longitudinal slot *d* in its upper part and, in its lower part, is formed with a longitudinal channel or trough *e* in which the lower edge of flat carriers *f* *f'* are adapted to run, the upper edges of the carriers projecting through the slot *d*, so that they are slidably guided within the rod.

A pulley g is mounted at one end of the rod a and a plug h formed with two parallel axial holes i i' is fitted in the other end. The pulley g as shown in Figure 3 is revolvably mounted on a spindle g' the lower end of which rests in the trough e and the upper end of which is screw threaded and extended through the slot d in the curtain rod. Nuts g^2 on the spindle g' are adapted to grip the rod a between them so that the spindle and pulley are fixedly held in the rod.

Each slideable carrier f f' is of flat formation suitably made of wood, vulcanite or fibre and formed at its leading end with a lug k having a recess k' for carrying a curtain ring l which supports the first or leading hook m of a curtain. The following end of each carrier is formed with a hump or cam surface o , one end of which terminates at the level, or slightly beneath the level, of the slot d of the curtain rod and the other end merges into a horizontal portion n which extends slightly above the level of the slot d towards the lug k . The bifurcated lugs k are directed towards the middle of the length of the curtain rod as shown. If desired, a metal band p , connected at its ends by a screw p' , encircles each end of the curtain rod a , the upper portion of each band being bent inwards to form a loop q which is adapted to permit the passage of the respective slideable carrier therethrough, and at the same time to limit the travel of the movable curtain rings towards the extremities of the rod.

The carriers f f' are adapted to be slideable simultaneously in the curtain rod by actuation of a cord j which is passed through the hole i in the plug h and through holes r r' formed in each end of the carrier f . From the latter, the cord is conducted round the pulley g through holes r r' similar to the holes r r' in the carrier f' and from thence it is led through the hole i' in the plug h . The ends of the cord j then hang down and are adapted to be actuated merely by the pull on one or other of the ends thereof to open or close the curtains.

As stated the first curtain ring l and hook m of each curtain are supported by the lug k while the last hook s is suspended from an eye t' mounted on the under surface of the bracket b . The remaining intermediate rings t are supported from the upper surface of the carriers or by that portion of the curtain rod situated between the stop device constituted by the metal band p , and the middle of the rod.

In operation and assuming that the curtains are closed and that it is desired to open them, the end j' of the cord is pulled and this results in the carriers f f' being drawn towards the ends of the curtain rod. During their travel the cam surfaces o engage the curtain rings t so that during the continued

travel of the carriers the rings are gradually forced over the humps or cams o on to the horizontal surfaces n . The lugs k cause the first hooks l to communicate the motion to the ends of the curtains and, as soon as each carrier engages the next ring resting on the horizontal upper surface of the rod, the succeeding portion of the curtain is caused to travel towards the end of the rod. In succession, the rings are gradually crowded on to each carrier so that each curtain is progressively opened or folded. The stop devices p serve for preventing the rings t from being pushed any further towards the ends of the rod while at the same time permitting the passage of the carriers, so that in the fully opened or folded condition of the curtains all the rings t are in position upon the carriers f f' , as shown in Figure 4, the sliding movement of the carriers f f' being limited by the pulley g and plug h , respectively.

In the event of its being desired to unfold or close the curtains, the end j' of the cord is pulled. This causes a travel of the carriers towards each other, so that the curtain rings t are gradually released from the carriers on to the curtain rod as the carriers slide along, the stationary end of the curtain being held by the eye t' and hook s . Each pleat of the curtain is completely drawn out before the next curtain ring is released due to the restraining action of the humps o . As shown in Figure 1 the last two rings of each curtain have been released from the carrier and a third is about to be dropped on to the curtain rod. However, the hump o retains this ring in position on the carrier so that the latter continues its travel towards the middle of the curtain rod until the pleat u is completely unfolded. Upon this taking place the ring in question readily comes into contact with the rod due to the inclination or curvature of the end of the carrier. The unfolding of the curtain proceeds in this manner until the carriers contact at their leading ends whereupon the curtains are fully unfolded. It will thus be seen that during the closing or unfolding of the curtain, no strain is imposed on the first hooks and transmitted to the leading end of the curtains. On the contrary, the arrangement permits the release of the rings which have reached the end of their travel from those carried by the moving parts of the curtain so that the first pleat is the last to be unfolded. Consequently, all detrimental strain on the curtain caused by the pull transmitted through the first and leading hooks, is avoided.

The modified construction of apparatus shown in Figures 5, 6 and 7 is similar to that just described, and shows a means which may suitably be provided for the drawing of a single curtain. The ends of the curtain rod a , provided with a slot d as before is fitted with pulleys which are preferably of material such

as vulcanite or fibre for producing noiseless running of the curtain drawing means. A grooved spherical pulley v is mounted on a vertical axis in a sleeve 3 fitted over and 5 clamped on one end of the curtain rod by a bolt 30, and two cylindrical grooved pulleys w w' are mounted on a horizontal axis in a sleeve 5 passed over the other end of the rod, the sleeve 5 having parts removed to 10 afford access to the actuating cord j . This cord is passed over the pulley w' threaded through holes x in the carrier y , passed over the spherical pulley v and thence to the sheave or pulley w' . The ends of the cord are 15 thus adapted for the manipulation of the carrier y so that it can be traversed from one end to the other of the curtain rod by sliding in the guideway e and the slot d formed in the rod. In opening or folding 20 the curtain, the appropriate end of the cord is pulled, whereupon the carrier travels from the right to the left hand end of the rod. The carrier has a lug k rising above the horizontal surface z disposed above the level of 25 the slot d in the curtain rod, as before. The other end of the carrier, however, terminates in a downwardly inclined surface y' extending to the level or beneath the level, of the slot d . Thus, the travel of the carrier 30 in one direction causes the curtain rings t to ride up the incline y' on to the horizontal portion z . The curtain rings are, therefore, conveyed with the carrier owing to the stop formed by the lug k as previously described. 35 A sleeve 1 is fixed around one end of the rod by a set screw 2 this sleeve being of such diameter that it arrests the last ring t' on contacting with the latter, consequently limiting the further movement of the following rings also, but permits the passage of 40 the carrier, so that when the folding or closing of the curtain is to take place, all the curtain rings t are in position on the carrier. The last hook of the curtain is supported from an extension 4 of a sleeve 3 in 45 which the spherical pulley v is mounted. In closing or unfolding the curtain, the carrier is traversed from left to right by actuating the appropriate end of the cord so that the 50 rings are gradually released from the carrier as the latter travels, as hereinbefore described.

Figure 8 illustrates a modified construction for the mounting of a double curtain. 55 Curtain rods 6 and 7 are formed with slots and provided with carriers 8 and stop devices 15 as hereinbefore described. The two rods are connected together at one end by a U-piece 9 in which a pulley 10 is mounted 60 and a double sleeve 11 is fitted over the other ends of the rods and supports a spindle 12 on which two pulleys 13, 14 are revolvably mounted.

Naturally, the section of the rod may be 65 other than circular and the rod may be curved

instead of straight. It is also contemplated that the slide or runner may take various forms. For example, as shown in Figure 9, it may be mounted externally instead of within the rod. As shown in this construction the curtain rod 26 is formed with a longitudinal slot 27 in its lower part and the carrier 28 surrounds the rod and is formed with an inward radial projection 29 engaging the slot 27 for guiding the carrier. The latter may be formed with a web 30 on its upper surface, this web having a lug 31 supporting the first curtain ring and having an inclined surface or hump, and a horizontal portion as described with reference to the preceding constructions. However, the upper surface of the carrier or carriers employed in connection with any one of the constructions described may be modified in any convenient manner, for facilitating the release and collection of the rings, during the unfolding and folding respectively of the curtain.

When used with curved or bent rods, as shown diagrammatically in Figure 10, the carrier 32 may be made of laminated material, or it may be a blade spring, so as to conform readily not only with the straight portions but also with the curved portions of the rod, the upper surface of such carrier being suitably formed as hereinbefore described.

In order to avoid the provision of a trough formation, such as e in Figure 1, for guiding the carrier, the latter may be formed, as shown in Figure 11 with part cylindrical blocks 33 connected to each of its flat sides, so that the carrier slidably fits within the curtain rod without risk of jamming. The cords j are threaded through holes r' and knotted at the ends.

When the invention is applied to large and particularly heavy curtains it may be necessary to employ intermediate supports for the rod, in addition to the brackets b , and in this case a portion of each of the rings t would have to be broken away to enable them to pass the intermediate supports, so that these slideable rings are then more in the nature of hooks.

I claim:—

1. Apparatus for the drawing of curtains comprising a curtain rod, curtain suspensory devices mounted on said rod, a carrier slidably guided along said rod, a hump formation on the upper surface of said carrier and a connection for the leading suspensory device of the curtain provided on the leading end of said carrier.

2. Apparatus for the drawing of curtains comprising a curtain rod, a slideable carrier, curtain suspensory devices mounted on said rod, a hump formation on the upper surface of said carrier, a lug formed on the leading end of said carrier adapted to carry the leading suspensory device of the curtain, and a cable threaded through said carrier, and

adapted to traverse said carrier along the rod.

3. Apparatus for the drawing of curtains comprising a curtain rod formed with a longitudinal slot in its upper portion, and having a guideway in its lower portion, cable guiding devices mounted in each end of said rod, a carrier slideable in said guideway with its upper surface projecting through the slot of said rod, a hump formation on the upper surface of said carrier, and a cable passed over said guiding devices and connected to said carrier.

4. Apparatus for the drawing of curtains comprising a curtain rod formed with a longitudinal slot in its upper portion and having a channel section guideway in its lower portion, curtain suspensory devices mounted on said rod, cable guiding devices mounted in each end of said rod, a flat carrier slideable in said guideway with its upper surface projecting through the slot of said rod, a lug connection for the leading curtain suspensory device on the forward end of said carrier, a hump formation adjacent the rear end of said carrier, and a cable passed over said cord guiding devices and connected to said carrier.

5. Apparatus for the drawing of curtains comprising a curtain support, curtain suspensory devices mounted on said support, fixed restraining means engaging one end of a curtain, a carrier bodily slideable along said support and having a portion of its upper surface projecting above the upper surface of the support for raising and lowering said suspensory devices during folding and unfolding of the curtain, a cable guiding device on said support, and a cable passed over said device and connected to said carrier for traversing said carrier along the curtain support.

6. Apparatus for the drawing of curtains comprising a curtain support, fixed restraining means on said support adapted for engaging one end of a curtain, curtain suspensory devices mounted on said support, a carrier mounted in said curtain support and bodily slideable along said support and having a portion of its upper surface projecting above the upper surface of the support for raising and lowering said suspensory devices during the folding and unfolding of the curtain, and means for traversing said carrier in the curtain support.

7. Apparatus for drawing of curtains comprising a horizontal slotted curtain rod, curtain suspensory devices mounted on said rod, a carrier bodily slideable along said support and having a portion of its upper surface projecting above the upper surface of the support for raising and lowering said suspensory devices, means for transversing said carrier along the rod, and a stop device for said

suspensory devices located at the end of the rod.

8. Apparatus for the drawing of curtains comprising a curtain rod, curtain suspensory devices mounted on said rod, a carrier bodily slideable along said support and having a portion of its upper surface projecting above the upper surface of the support for raising and lowering said suspensory devices formed with an upper surface adapted for coacting with the suspensory devices to retard their release from the carrier on to the rod, and means for traversing said carrier along the curtain rod.

9. Apparatus for drawing curtains comprising a horizontal curtain support, curtain suspensory devices mounted on said support, a carrier bodily slideable along said support and having a portion of its upper surface projecting above the upper surface of the support for raising and lowering said suspensory devices during folding and unfolding of the curtain, a connection on the end of said carrier for the leading curtain suspensory device, and a fixed connection on the support for the last suspensory device.

10. Apparatus for the drawing of curtains comprising a curtain rod formed with a longitudinal slot in its upper portion, curtain suspensory devices mounted on said rod, a flat carrier bodily slideable along said devices and having a portion of its upper surface projecting through the slot, said upper surface being adapted for coacting with the suspensory devices to retard their release from the carrier on to the rod, and means for traversing said carrier along the rod.

11. Apparatus for the drawing of curtains comprising a curtain rod, curtain suspensory devices mounted on said rod, a carrier bodily slideable along said rod and having a portion of its upper surface projecting above the upper surface of said rod for raising and lowering said suspensory devices, a connection for the leading curtain suspensory device formed on said carrier, a fixed connection on the support for the last suspensory device, a cable guiding device on said rod, and a cable passed over said device and connected to said carrier for traversing said carrier along the curtain rod.

12. Apparatus for drawing curtains comprising a horizontal tubular curtain rod formed with a longitudinal slot in its upper portion, fixed restraining means engaging one end of a curtain, suspensory devices mounted on said rod, a carrier bodily slideable along said rod and having a portion of its upper surface projecting above the upper surface of said rod for raising and lowering said suspensory device and adapted for carrying the curtain suspensory devices during movement of the curtain, and stop means mounted adjacent the end of said rod in the path of said suspensory devices.

13. Apparatus for drawing curtains comprising a curved support, a curtain suspensory device mounted on the latter and a flexible carrier bodily slideable along said support and having a portion of its upper surface projecting above the upper surface of the support for raising and lowering said suspensory device during folding and unfolding of the curtain.
